CLAIM

The ornamental design for a control apparatus for a soldering iron, as shown and described.

DESCRIPTION

FIG. 1 is a perspective view of a control apparatus for a soldering iron embodying our new design.

FIG. 2 is a back view of the control apparatus for a soldering iron of FIG. 1.

FIG. 3 is a bottom view of the control apparatus for a soldering iron of FIG. 1.

FIG. 4 is a front view of the control apparatus for a soldering iron of FIG. 1.

FIG. 5 is a left side view of the control apparatus for a soldering iron of FIG. 1.

FIG. 6 is a right side view of the control apparatus for a soldering iron of FIG. 1; and,

FIG. 7 is a top view of the control apparatus for a soldering iron of FIG. 1.

The broken lines depict portions of the control apparatus in which the design is embodied that are not considered part of the claimed design.
